UNITED STATES PATENT OFFICE

152,429

DESIGN FOR A COMBINED ANTENNA AND
SUPPORT THEREFORSidney Ludwig, Cleveland Heights, and Robert R.
Cull, Brecksville, Ohio

Application January 27, 1947, Serial No. 136,457

Term of patent 7 years

(Cl. D14—6)

To all whom it may concern:

Be it known that we, Sidney Ludwig and Robert R. Cull, both citizens of the United States, residing at Cleveland Heights and Brecksville, respectively, both in the county of Cuyahoga, State of Ohio, have invented a new, original, and ornamental Design for a Combined Antenna and Support Therefor, of which the following is a specification, reference being had to the accompanying drawing, forming a part thereof:

Figure 1 is a side elevational view of a combined antenna and support therefor, showing our new design, the dot and dash lines appearing in Figure 1 being solely for illustrative purposes; and

Figure 2 is a top plan view thereof.

In both figures portions have been broken away for convenience of illustration.

We claim:

The ornamental design for a combined an-

tenna and support therefor, as shown and described.

SIDNEY LUDWIG.
ROBERT R. CULL.
